UNITED STATES PATENT OFFICE.

ROY W. SEXTON, OF WYTHEVILLE, VIRGINIA.

STAMPING EMBROIDERY-FORMS.

1,360,804.

Specification of Letters Patent. Patented Nov. 30, 1920.

Application filed January 28, 1918. Serial No. 214,260.

To all whom it may concern:

Be it known that I, Roy W. SEXTON, a citizen of the United States, and a resident of Wytheville, county of Wythe, and State of Virginia, have invented certain new and useful Improvements in Stamping Embroidery-Forms, set forth in the following specification.

This invention relates to embroidery forms and the manufacture thereof.

The object of the invention is to produce a tough, sufficiently stiff embroidery form having the necessary flexibility and particularly one cheap and inexpensive to manufacture.

The above and further objects of the invention will better be understood by reference to the accompanying drawings which form a part hereof, in which like characters designate corresponding parts in the figures and toward which, as illustrative of the invention, the following specification is directed.

In the drawings Figure 1 is a diagrammatic representation of a press in which embroidery forms are being stamped; and Fig. 2 is a vertical section through line II—II of Fig. 1 but drawn to an enlarged scale and with parts broken away.

Heretofore it has been found necessary, when cutting embroidery forms out of sheet material through the medium of dies, to dust the operating faces of the dies with powdered soap-stone, otherwise the dies became clogged and great difficulty was experienced in removing an embroidery form without breaking its more delicate parts. This dusting with soap-stone was, of course, necessary for each operation of the press. By practising my invention this time taking step is eliminated and, in addition, embroidery forms of stronger, more durable character are produced.

I start with a sheet or bolt of compacted fibers, preferably a sheet of compacted cotton felt. I form a solution of wax in a volatile solvent. I prefer to employ paraffin and gasolene, although I contemplate any suitable stiff wax such as beeswax and any of the volatile solvents such as the many in the hydrocarbon group. When employing paraffin and gasolene I prefer to dissolve one pound of paraffin in one gallon of gasolene.

This solution is then caused to saturate the sheet of cotton felt which is subjected to pressure while still wet with gasolene under 55 conditions permitting the evaporation of the volatile solvent. For example, absorbent material may be situated on both sides of the saturated cotton felt when it is being subjected to pressure. For some purposes I 60 contemplate incorporating the paraffin into the cotton felt for less than its entire cross section, preferably from what is to be the top surface of the embroidery form downwardly to a more or less greater extent. 65 Part of the advantages of my invention are attained with only a slight extent of the cross section being incorporated with the paraffin.

The pressure and, if necessary, heat is 70 continued until all the volatile solvent is removed, when the finished body of embroidery form material should be cooled sufficiently to solidify the incorporated wax. A sheet 1 of this body fabric is then backed 75 with straw-board 2. The surface 3 of the body fabric 1, which is intended to form the top surfaces of the finished embroidery forms, is placed downwardly upon the cutting dies 4 usually mounted on blocks 5 80 upon the bed *a* of the press A. The press is operated to cause the stamp 6 to exert a uniform pressure against the straw-board 2 until each die 4 cuts out an embroidery form 7 and molds its finished surface 8 into conformity with the curved face 9 of the die 4. The incorporated paraffin greatly assists the molding of the fabric into the desired cross section. In Fig. 2 the press is shown open after the stamping of the embroidery form has been effected and clearance is indicated between the embroidery form 7 and the die 4, which actually takes place, the paraffin serving to effect a clean 90 clearance of all parts of the embroidery form from the die.

Although I have described the use of either paraffin or beeswax, I contemplate the use of any material having similar properties and likewise the use of any suitable 100 volatile solvent for such filling material selected. However, I believe that the filling material employed should be waxy and substantially solid at normal temperatures but

capable of flowing under heavy pressure. The term "wax," as employed in the claims, is intended to embrace not only beeswax but other materials the equivalent thereof for the purposes of the invention.

What I claim and desire to secure by United States Letters Patent is:—

- 10 1. A filler form for embroidery embodying an embroidery design and adapted to be covered by embroidery threads made of a body of fibers having an impregnation of wax.
- 15 2. A filler form for embroidery embodying an embroidery design and adapted to be covered by embroidery threads comprising a body of compacted fibers having a filling of wax extending inwardly from a surface.
- 20 3. A filler form for embroidery embodying an embroidery design and adapted to be covered by embroidery threads comprising a body of compacted fibers having a filling

of wax extending downwardly from the top surface.

4. A filler form for embroidery embodying an embroidery design and adapted to be 25 covered by embroidery threads comprising a body of compacted cotton fibers having a filling of wax extending downwardly from the top surface.

5. The process of producing embroidery 30 forms comprising dissolving wax in a volatile solvent, applying the dissolved wax and solvent to a sheet of compacted fibers, evaporating out the volatile solvent, and applying pressure to the back face of said 35 sheet of compacted fibers while the front face is in contact with a die.

In testimony whereof I have signed my name to this specification, this 8th day of January, 1918.

ROY W. SEXTON.
